TONGS

Helen K. Williams and Edwin G. Williams,
Pompano Beach, Fla.

Application December 28, 1953, Serial No. 28,254

Term of patent 14 years

(Cl. D44—4)

To all whom it may concern:

Be it known that we, Helen K. Williams and Edwin G. Williams, citizens of the United States, residing at Pompano Beach, in the county of Broward and State of Florida, have invented a new, original, and ornamental Design for Tongs, of which the following is a specification, reference being had to the accompanying drawing, forming part thereof.

Figure 1 is a perspective view of a pair of tongs, showing our new design and illustrating the same in the closed position;

Figure 2 is a perspective view thereof in the open position; and,

Figure 3 is a cross-sectional view, taken along line 3—3 in Figure 2.

We claim:

The ornamental design for tongs, as shown.
